COMPARTMENTED TRAY

Herbert A. Clemens, Fort Wayne, Ind., assignor to National Packaging Corporation, Fort Wayne, Ind.

Filed Sept. 4, 1959, Ser. No. 57,447

Term of patent 14 years

(Cl. D58—13)

Fig. 1.

Fig. 2.

Fig. 3.

FIG. 4.

FIG. 5.

FIG. 1 is a top plan view of the compartmented tray, showing my new design, one-half of the tray being shown in phantom lines to indicate repetition of the design;

FIG. 2 is a side view of the tray of FIG. 1;

FIG. 3 is a fragmentary bottom plan view of the compartmented tray shown in FIG. 1;

FIG. 4 is an end view of the tray of FIG. 1; and

FIG. 5 is a fragmentary view in perspective of one corner portion of the tray as viewed from the lower right-hand corner in FIG. 1.

I claim:

The ornamental design for a compartmented tray, substantially as shown and described.
